(57) **CLAIM**

The ornamental design for the kitchen utensil handle, as shown and described.

DESCRIPTION

FIG. 1 is a perspective view of the kitchen utensil handle on a kitchen utensil.

FIG. 2 is a front perspective view of the kitchen utensil handle.

FIG. 3 is a rear perspective view of the kitchen utensil handle.

FIG. 4 is a bottom view of the kitchen utensil handle.

FIG. 5 is a top view of the kitchen utensil handle.

FIG. 6 is a right side view of the kitchen utensil handle.

FIG. 7 is a left side view of the kitchen utensil handle.

FIG. 8 is a front view of the kitchen utensil handle; and,

FIG. 9 is a rear view of the kitchen utensil handle.

The broken lines in the drawings form no part of the claimed design.

1 Claim, 6 Drawing Sheets
